[57] **CLAIM**

The ornamental design for a snap-on support for a cylinder rod to prevent closure of an automobile hatchback, as shown and described.

DESCRIPTION

FIG. 1 is a top plan view of a snap-on support for a cylinder rod to prevent closure of an automobile hatchback showing our new design, the bottom being a mirror image;
FIG. 2 is a rear elevational view thereof;
FIG. 3 is a left side elevational view thereof, the right side being a mirror image of that shown;
FIG. 4 is a front elevational view thereof; and,
FIG. 5 is a bottom rear, and left side perspective view thereof.
